SPINDLE FEED MECHANISM

Lora E. Poole, Anderson, Ind., assignor, by mesne assignments, to General Motors Corporation, Detroit, Mich., a corporation of Delaware

Original application August 9, 1929, Serial No. 384,715. Divided and this application June 9, 1933, Serial No. 674,985. Also a refile of abandoned application Serial No. 366,672, May 28, 1929.

6 Claims. (Cl. 77—32)

This invention relates to a metal working machine and in particular to a drill press head which is adapted to automatically advance a rotary tool such as a drill, a reamer or a counter-sink toward a work piece and to retract the tool from the work piece.

This application is filed in place of my abandoned application Serial No. 366,672 filed May 28, 1929 and is a division of my co-pending application Serial No. 384,715 filed August 9, 1929.

An object of this invention is to adjust the tool carrier relative to the work piece. This has been accomplished by providing a pair of members one of which terminates in a frusto-conical portion and the other having a recess with a frusto-conical inner surface, cooperating with the frusto-conical surface of said first member to hold the carrier in adjusted position and providing means for securing said members in adjusted position.

Another object of this invention is to limit the distance through which the tool carrier may be adjusted. This has been accomplished by a pin carried by one of the adjusting members which travels in an arcuate slot in the other member. The relative movement of the two members is limited by the pin engaging the ends of the arcuate slot.

Further objects and advantages of the present invention will be apparent from the following description, reference being had to the accompanying drawings, wherein a preferred form of the embodiment of the present invention is clearly shown.

In the drawings:

Fig. 1 is a side elevation of the machine.

Fig. 2 is a sectional view taken on the line 2—2 of Figs. 4, 5, 6 and 7.

Fig. 3 is a fragmentary sectional view taken on the line 3—3 of Figs. 6 and 7.

Figs. 4, 5, 6 and 7 are sectional views taken on the lines 4—4, 5—5, 6—6 and 7—7 of Fig. 2.

Fig. 8 is a fragmentary sectional view taken on the line 8—8 of Fig. 6.

Fig. 9 is a fragmentary sectional view taken on the line 9—9 of Fig. 7.

In the drawings the reference character 20 indicates an electric motor mounted on the housing 21, which forms a cap for the main frame 22. The gear 24 mounted on the armature shaft 26 meshes with a gear 28, keyed to a tubular sleeve 30 and held in position by a collar 32 threadedly engaging the end of the tubular sleeve 30, which is journalled in the end thrust bearings 33 and 35.

A spindle 34 is splined in the tubular member 30 and is journalled in the bearing 36. The spindle 34 terminates in a tool carrying end 38, which has not been shown in detail as any suitable tool carrier or chuck adapted to carry a tool, such as, a drill or a reamer may be used. Endwise movement of the spindle 34 relative to a quill 40 is prevented by a shoulder 42 integral with the spindle 34 and a nut 44 threadedly engaging the end 38, the shoulder and the nut abutting the inner race 36a of the roller bearing 36. The outer race 36b is held in position by a nut 37 engaging the flared end 41 of the quill 40. A key 48 seated in the frame 22 cooperates with a slot 50 in the quill 40 which permits longitudinal movement and prevents rotary movement of the quill as may best be seen in Figs. 2 and 7.

A suitable mechanism for feeding the tool carrier or spindle 34 and the quill 40 longitudinally toward the work piece will now be described. The tubular sleeve 30 is provided with a worm 52 meshing with a worm gear 54, keyed to the shaft 56, which carries a spur gear 58 (see Figs. 2 and 5). The shaft 56 is journalled in bearings 60 and 62 mounted in the frame 22 and held in position by screws 64 and 66, respectively. The spur gear 58 meshes with a gear 68 (see Figs. 1 and 6), keyed to a tubular member 69 rotatably mounted on the shaft 70, journalled in bearings 72 and 76 which are mounted in the gear retaining cap 78 and the end frame 80, respectively, each of which are attached to the frame 22 by suitable screws. Intermediate the tubular member 69 and the shaft 70 is mounted a bushing 79. Member 69 terminates in radial teeth 82 which cooperates with teeth 84 integral with member 86 splined on the shaft 70 as best seen in Fig. 8. Also splined on the shaft 70 is a spiral cam 182 which cooperates with a cam follower 85 mounted on a pin 87 carried by a Z-shaped rack 88 and held in position by a set screw 89. As the cam 182 is rotated, the rack 88 will be urged to the left as viewed in Figs. 2 and 3, so as to feed the tool carrier or the spindle 34 towards the work piece through a driving connection consisting of a gear member 92 which is rotatably mounted on a shaft 94 meshing with the teeth 93 on the rack 88. The forces acting upon rack 88 are so directed that couples or turning movements are set up that tend to neutralize each other thereby reducing friction and the power required to actuate the rack. Gear 92 cooperates with a gear member 112 splined to shaft 94 and meshing with teeth 113 provided therefor on the quill 40.

Gear 92 terminates in a frusto-conical surface 55

Operation

- 92a cooperating with a recess in gear member 112 having a frusto-conical inner surface to permit the adjustment of the distance of the work carrier from the workpiece. Members 92 and 112 are held in frictional engagement by a nut 126 threadedly engaging the end of the shaft 94 and by a shoulder 120 provided by a collar 122 integral with the shaft 94. Upon the loosening of the nut 126 member 112 is biased from member 92 by a helical spring 118, mounted on the shaft 94 and positioned in a recess in member 92 provided therefor. The adjustment of the work carrier or spindle 34 is limited by a pin 114 carried by member 112 which travels in an arcuate slot 116 in member 92. As best seen in Fig. 2, gear members 92 and 112 are limited in their relative angular movement by the length of the slot 116 to such an extent that gear 92 in either end position of adjustment never demeshes from the rack 113 under all circumstances. The end of the shaft 94 terminates in a square portion 128 which permits the operator to adjust the spindle 34 without dismounting the machine.
- The mechanism for retracting the work spindle 34 from the work piece comprises a spiral spring 98 which has a hooked end 96 engaging a recess provided therefor in a cylindrical portion 102, integral with gear 92 and the hooked end 103 engaging a recess in the cup shaped member 104 which is rotatably mounted in the end frame 80. In order to adjust the tension of the spring 98 member 104 has been provided with a ratchet 105 which cooperates with a pawl 106 mounted on a pin 108 carried by the end frame 80. Any suitable means such as a collar 108a is mounted on pin 108 (see Fig. 7) to permit the manual withdrawal of pawl 106 from the ratchet 105 in case it is desired to decrease the tension of spring 98 as can be readily understood. The spring 98 urges the spindle 34 away from the work piece and the cam follower 85 to the right as viewed in Fig. 2.
- A device has been provided to stop the mechanism from reciprocating the spindle 34 after it has been retracted to the right as viewed in Fig. 2.
- This stopping device consists of a cam projection 130 integral with a member 86, which engages a releasing lever 132 mounted on the pivot 134 carried by the frame 22. In Figs. 6 and 8, it may be seen that as the cam projection 130 strikes the lever 132, member 86 will be biased against the force of the helical spring 136 so as to disengage the radial teeth 82 and 84 whereby member 69 will rotate without rotating member 86 and the part driven thereby. When the operator desires to have the spindle 34 reciprocated he presses inwardly on a rod 139, pivotally connected to lever 132, against the action of a spring 140 so as to rotate the lever 132 in a counterclockwise direction as viewed in Fig. 2 whereby lever 132 clears the cam projection 130 permitting the spring 136 to actuate member 86 so that the teeth 82 and 84 will engage. If it is desired to use the drill press with an automatic work presenting device, suitable means may be provided to either hold lever 132 in such a position that it will at all times, clear the cam projection 130 or to automatically release lever 132 at the end of predetermined time intervals or upon the happening of predetermined events.
- A felt washer 150, which may be impregnated with oil, supplies oil to the end-thrust bearing 35, and is retained in position by the collar 151, biased to the right, as viewed in Fig. 2, by a helical spring 152, bearing against an annular ring 153, held in the frame 22.

A brief recapitulation of the mechanism and its operation will now be described as follows: The automatic drill head comprises a rotatable and longitudinally slidably tool carrier or spindle 34 carried in the frame 22 by means of the sleeve 30 and the quill 40, the sleeve 30 being rotatably mounted at one end of the frame and serving to rotate the spindle 34 which is splined in this sleeve for slidable movement therein, and the quill 40 being slidably and non-rotatably mounted at the other end of the frame and serving to advance and retract the spindle 34 to and from the work. Sleeve 30 is provided with the worm 52 which meshes with a worm gear 54 for actuating the feeding mechanism, which comprises a rotatable cam 182 contacting with a cam follower 85 secured to a rack 88 having a driving connection with the quill 40 through a pair of frictionally engaging members 92 and 112 adapted to permit the adjustment of the spindle 34 with respect to the work. The spring 98 retracts the slidably quill 40 and the spindle 34 at the end of each revolution of the spiral cam 182. Interposed between the worm gear 54 and the spiral cam 182 is a clutch of which one element 86 carries a cam 130 which separates the two clutch elements 86 and 69 at the end of a retracting movement by contacting with a spring pressed lever 132 which is manually or otherwise controllable for permitting the two clutch elements to engage each other, the clutch elements being urged together by a spring 136.

Referring to Figs. 5, 6 and 7, the frame 22 has an extension 160 which is somewhat dove-tail shaped in cross section and which is adapted to slide between suitable "ways" provided by a machine frame, not shown, with which the drill head is intended to cooperate. It will be understood by those skilled in this art that after the drill head has been moved along the "ways" of the machine frame it may be clamped in adjusted position.

While the form of embodiment of the present invention as herein disclosed, constitutes a preferred form, it is to be understood that other forms might be adopted, all coming within the scope of the claims which follow.

What is claimed is as follows:

1. In a tool operating device, the combination of a housing open at one side; a tool carrying spindle reciprocably supported by the housing and having a rack therein; a gear meshing with the rack and having a frusto-conical surface and a hub journaled in a wall of the housing opposite the open end thereof; an end frame detachably secured to the housing for closing the same; a bearing in the end frame; a shaft having a shoulder and being journaled at one end in said bearing and splined at the other end to the gear, said other shaft end extending beyond the gear and being threaded and terminating in a square portion to permit manual rotation of the shaft from the outside of the housing; another gear loosely mounted on the shaft and having a frusto-conical surface adapted frictionally drivingly to engage that of the first mentioned gear; a spring between both gears normally urging the first mentioned gear out of driving engagement with said other gear; a nut received by the threaded shaft portion and engaging the first mentioned gear to force the same into driving engagement with said other gear and the latter into engagement with the shaft shoulder; and a reciprocable rack

meshing with said other gear for rotating the same.

2. In a tool operating device, the combination of a housing open at one end; a tool carrying 5 spindle reciprocably supported by the housing and having a rack therein; a gear meshing with the rack and having a frusto-conical surface and a hub journaled in a wall of the housing opposite the open end thereof; an end frame detachably secured to the housing for closing the same; a cup-shaped member journaled in the end frame; means for preventing rotation of the member in one direction; a bearing in the member; a shaft having a shoulder and being journaled at one 10 end in said bearing and splined at the other end to the gear, said other shaft end extending beyond said gear and terminating in a square portion to permit manual rotation of the shaft from the outside of the housing; another gear loosely mounted on the shaft and having a frusto-conical surface adapted frictionally drivingly to engage that of the first mentioned gear; means co-operating with the shaft for forcing the first mentioned gear into driving engagement with 15 said other gear and the latter into engagement with the shaft shoulder; a tensioned spiral spring secured with one end to the member and with the other end to said other gear and normally tending to rotate the latter in a direction opposite to said one direction; and a reciprocable rack meshing with said other gear for rotating the same.
3. In a tool operating device, the combination of a housing open at one side; a tool carrying 20 spindle reciprocably supported by the housing and having a rack therein; a gear meshing with the rack and having a frusto-conical surface and a hub journaled in a wall of the housing opposite the open end thereof; an end frame detachably secured to the housing for closing the same; a cup-shaped member provided with a ratchet and having a hub journaled in the end frame and extending to the outside of the closed housing to permit manual rotation of the member therefrom; a bearing in the hub of the member; a shaft having a shoulder and being journaled at one end in said bearing and splined at the other end to the gear, said other shaft end 25 extending beyond the gear and being threaded and terminating in a square portion to permit manual rotation of the shaft from the outside of the housing; another gear loosely mounted on the shaft and having a frusto-conical surface 30 adapted frictionally drivingly to engage that of the first mentioned gear; a spring between both gears normally urging the first mentioned gear out of driving engagement with said other gear; a nut received by the threaded shaft portion and 35 engaging the first mentioned gear to force the same into driving engagement with said other gear and the latter into engagement with the shaft shoulder; a tensioned spiral spring secured with one end to the cup-shaped member and with its other end to said other gear and normally tending to rotate the latter in a direction opposite to said one direction; and a reciprocable rack meshing with said other gear for 40 rotating the same.
4. In a tool operating device, the combination of a housing open at one side; a tool carrying 45 spindle reciprocably supported by the housing and having a rack therein; a gear meshing with the rack and having a frusto-conical surface and a hub journaled in a wall of the housing opposite the open end thereof; an end frame detachably secured to the housing for closing the same; a cup-shaped member journaled in the end frame; means for preventing rotation of the member in one direction; a bearing in the member; a shaft having a shoulder and being journaled at one end in said bearing and splined at the other end to the gear, said other shaft end 50 extending beyond the gear and being threaded and terminating in a square portion to permit manual rotation of the shaft from the outside of the housing; another gear loosely mounted on the shaft and having a frusto-conical surface 55 adapted frictionally drivingly to engage that of the first mentioned gear; a nut received by the threaded shaft portion and engaging the first mentioned gear to force the same into driving engagement with said other gear and the latter into engagement with the shaft shoulder; a tensioned spiral spring secured with one end to the cup-shaped member and with its other end to said other gear and normally tending to rotate the latter in a direction opposite to said one direction; and a reciprocable rack meshing with said other gear for 60 rotating the same.
5. In a tool operating device, the combination of a housing open at one side; a tool carrying 65 spindle reciprocably supported by the housing and having a rack therein; a gear meshing with the rack and having a frusto-conical surface and a hub journaled in a wall of the housing opposite the open end thereof; an end frame detachably secured to the housing for closing the same; a cup-shaped member provided with a ratchet and having a hub journaled in the end frame and extending to the outside of the closed housing to permit manual rotation of the member therefrom; a pin rotatably mounted in the end frame; a pawl mounted on said pin and 70 operating with the ratchet inside the housing to 75

- prevent rotation of the ratchet in one direction; a manually rotatable collar mounted on the pin outside the closed housing for withdrawing the pawl from the ratchet; a bearing in the hub of the member; a shaft having a shoulder and being journaled at one end in said bearing and splined at the other end to the gear, said other shaft end extending beyond the gear and being threaded and terminating in a square portion to permit manual rotation of the shaft from the outside of the housing; another gear loosely mounted on the shaft and having a frustro-conical surface adapted frictionally drivingly to engage that of the first mentioned gear; a spring

between both gears normally urging the first mentioned gear out of driving engagement with the other gear; a nut received by the threaded shaft portion and engaging the first mentioned gear to force the same into driving engagement with said other gear and the latter into engagement with the shaft shoulder; a tensioned spiral spring secured with one end to the cup-shaped member and with its other end to said other gear and normally tending to rotate the latter in a direction opposite to said one direction; and a rack meshing with said other gear for rotating the same. 5

LORA E. POOLE.
